[57] CLAIM

The ornamental design for a component mounting machine, as shown.

DESCRIPTION

FIG. 1 is a front perspective view of a component mounting machine according to the invention;

FIG. 2 is a rear perspective view of a component mounting machine according to the invention;

FIG. 3 is a front view of a component mounting machine according to the invention; and,

FIG. 4 is a rear view of a component mounting machine according to the invention.

FIG. 1

FIG. 2

FIG. 3

FIG. 4
